POODLE DOG WALL PLAQUE OR THE LIKE

William V. Deane, 105 S. Commonwealth,
Los Angeles, Calif. 90004

Filed Feb. 18, 1966, Ser. No. 1,114

Term of patent 14 years

(Cl. D29—23)

FIGURE 2 is a side elevation of another embodiment of the poodle dog plaque shown in FIGURE 1 wherein the over-all outline of a French poodle is depicted with a Royal Dutch Clip; and

The cut-outs extend evenly over the forebodies and heavy leg portions of each of the poodles depicted in FIGURES 1 and 2.

I claim:

The ornamental design for a poodle dog wall plaque or the like, substantially as shown and described.
